UNITED STATES PATENT OFFICE.

LEONARD R. STEEL, OF CLEVELAND, OHIO.

ICE-CREAM-STORAGE CAN.

1,016,974.

Specification of Letters Patent. Patented Feb. 13, 1912.

Application filed March 8, 1911. Serial No. 613,039.

To all whom it may concern:

Be it known that I, LEONARD R. STEEL, a citizen of the United States, residing at Cleveland, in the county of Cuyahoga and

5 State of Ohio, have invented new and useful Improvements in Ice-Cream-Storage Cans, of which the following is a specification.

This invention relates to ice cream storage 10 cans.

The primary object of the invention is to provide a can including an outer jacket and an inner liner or vessel, the latter being constructed of glass and being removable from 15 the jacket and being provided with means whereby its walls will be spaced from the walls of the jacket so as to prevent the liner from becoming broken should the walls of the jacket become mutilated in handling.

20 Another object of the invention is to provide the liner and jacket respectively, with individual covers so as to protect the ice cream from salt in packing.

Another object of the invention is to provide 25 an improved form of crate or basket for supporting the liner in the jacket, the construction of the crate or basket being such that it may be lifted from the jacket with the liner, thereby obviating the necessity of removing the jacket from its ice packing.

In the drawing, forming a portion of this 30 specification and in which like numerals of reference indicate similar parts in the several views:—Figure 1 is a vertical section through the can. Fig. 2 is a horizontal section therethrough on line 2—2 of Fig. 1. Fig. 3 is a plan view of the can with the cover of the jacket removed.

40 The can comprises a substantially cylindrical outer jacket 1 and a substantially cylindrical inner glass liner 2. The jacket 1 is provided at one end with a bottom member 3 having a depending flange 4 which is 45 embraced by the lower walls of the jacket.

An inner reinforcing band 5 is embraced by the flange 4 and it is secured thereto and to the walls of the jacket by fastening rivets 5'. At the upper end the jacket is provided 50 with a relatively large portion 6 to which is removably fitted a cover 7. This cover is provided with a suitable handle 8.

The liner 2 is fitted in a basket or crate 9. The basket includes a substantially U- 55 member 10 having vertical portions 11. The vertical portions of the member are pro-

vided at their upper ends with eyes 12 in which the eyes 13 of a lifting bail 14 are operatively connected. The vertical portions 11 of the member are secured to inner 60 spacing bands 15. These bands serve to hold the vertical walls of the liner spaced from the vertical walls of the jacket. At the upper end the liner is provided with a reduced portion 16, being offset inwardly so 65 as to be spaced a considerable distance from the large end 6 of the jacket to form an intervening channel. The eyes 12 of the vertical members 10 are arranged in the channel between the portion 16 of the liner 70 and the portion 6 of the jacket when the former is in the latter, as shown in Fig. 1 of the drawings. This channel also receives the bail 14. The bail is provided with an intermediate loop 17 which extends above 75 the plane of the top of the liner so as to allow for convenient movement of the bail to an operative position when it is desired to remove the liner from the jacket. The liner is provided with a cover 18 having a flange 19 which exteriorly fits the portion 16 of the liner. A paper disk 20 is located beneath the cover 18 so as to prevent the ice cream from coming in contact with any metal part 80 of the can. The cover 18 carries a suitable 85 handle 21. The vertical walls of the liner 2 are curved into the bottom of the liner, at 22, so as to greatly facilitate cleaning of the liner and prevent the accumulation on the bottom thereof of foreign matter. The 90 liner is graduated vertically, at 23, so that the exact contents of the liner can be readily ascertained, thereby enabling the purchaser of the cream to quickly learn whether or not he has received correct weight or amount 95 of material.

The can described and illustrated herein is extremely simple and has been found most desirable when used for freezing, storing, delivering, or dispensing ice cream, its parts being such that they may be conveniently separated from each other so that they can be kept in a perfect sanitary condition. The can thoroughly protects the ice cream against salt in packing in that the liner and jacket respectively, are provided with individual covers. The ice cream is further held against coming in contact with the salt in packing in that it is held securely housed by the jacket, the latter being fully 105 exposed to the action of the refrigerant.

The portion 17 of the bail is extended

above the plane of the top of the liner so as to permit it to be conveniently and quickly grasped when it is desired to withdraw the liner from the jacket.

5 I claim:—

An ice cream can comprising a jacket having a portion at its upper end of increased diameter, the liner removably fitted in the jacket and having a portion at its upper 10 end of decreased diameter, the upper portions of the jacket and liner respectively being spaced to form an intervening annular channel, a basket receiving the liner and

having ear portions disposed in the channel, a bail supported by the ears and provided 15 with an intermediate looped portion extending above the plane of the top of the liner, a cover for the liner, and a cover for the jacket.

In testimony whereof I affix my signature 20 in presence of two witnesses.

LEONARD R. STEEL.
